L. ATWOOD.
MANUFACTURE OF OILS.

No. 27,767.

Patented Apr. 10, 1860.

Luther Atwood

UNITED STATES PATENT OFFICE.

LUTHER ATWOOD, OF NEW YORK, N. Y.

IMPROVEMENT IN THE DISTILLATION OF HYDROCARBON OILS.

Specification forming part of Letters Patent No. 27,767, dated April 10, 1860.

To all whom it may concern:

Be it known that I, LUTHER ATWOOD, of the city, county, and State of New York, have invented certain new and useful Improvements in the Manufacture of Oils; and I do hereby declare that the following is a full and exact description thereof, reference being had to the annexed drawings, forming a part of this schedule, and to the letters of reference thereon.

In the distillation of hydrocarbon oils at a high temperature cast-iron stills are used, which become heated during the operation to a red heat, and it has heretofore been the practice to remove the fire after the completion of the distillation and wait for the still to cool down naturally to a very moderate temperature before removing the residue, the operator entering the still through the man-hole for that purpose; also, in commencing the next succeeding distillation the crude oils are poured into the still when it is cold, or nearly so, and care exercised to apply the heat so gradually as to prevent foaming of the contents.

My improvements avoid in great part the loss of time between successive distillations consequent upon the old mode of working such stills.

The nature of the first part of my invention consists in introducing into a hydrocarbon or volatile oil still after the completion of the distillation steam from a steam-boiler through any suitable pipe or inlet in sufficient quantities to expel through any suitable outlet the oleaginous vapors and fixed gases remaining in the still, and also to rapidly cool the still sufficiently to permit of the immediate removal of the carbonaceous residue.

The second part of my invention consists in introducing into the still after the residue is removed and the man-holes covered and luted, and before charging the still with crude oil, steam from a steam-boiler through any suitable inlet or pipe in sufficient quantities to expel through any suitable outlet the atmospheric air from the hot still, preparatory to the admission of the charge of oil, and for the purpose of preparing a hot still for the introduction of a charge of oil without danger of ignition or explosion.

In order to more particularly describe my invention, I will refer to the annexed draw-

ings, which represent a still of improved construction the subject of contemporaneous Letters Patent of the United States to me, and which show the form of apparatus I consider most convenient and best adapted to embody and carry out the invention herein described. I do not, however, intend to limit myself to the use of this form of construction therein shown, but will use any convenient form of construction that will enable me to practice my invention.

Figure No. 1 of the drawings represents a plan view of the still; Fig. No. 2, a front elevation; Fig. No. 3, a horizontal section through dotted lines *xx*, Fig. 2; Fig. No. 4, a horizontal section through dotted lines *yy*, Fig. 2; Fig. No. 5, a transverse section through dotted lines *xx*, Fig. 1; Fig. No. 6, a vertical longitudinal section through dotted lines *yy*, Fig. 1.

Having described minutely the construction and operation of the still represented by the above-mentioned drawings in contemporaneous Letters Patent, I will only describe in this specification such parts as are immediately connected with the invention herein described.

Letter A represents the body or boiler of a still; B, a pipe connecting the worm-condenser with the dome of the still through the angle-valve or shut-off C.

D is a weighted safety-valve on the dome of the still, connecting by the blow-off pipe E with the main F, from which opens the discharge-pipe G. The stem of the safety-valve is fitted to receive the slotted weight D' and terminates in a ring-handle, by which it may be lifted and hooked onto the hook D''. When thus lifted, there is a free passage from the still through the safety-valve, blow-off pipe E, main F, and discharge-pipe G to the open air.

H H are two man-holes in the top of the still furnished with suitable covers and fastenings. Letter I represents a funnel-pipe provided with a stop-cock opening into the top of the still, and J a pipe provided with a stop-cock. (Shown broken off, but designed to connect the still with a reservoir of unfinished oil.)

Letter K is a steam-pipe furnished with a stop-cock. The lower end of this pipe enters the still, connecting with a steam-boiler by a 4-coupling and steam pipe L. (Shown broken off.) While the still is in action the

angle-valve C in the passage between the still and condenser is kept open and the passage to the open air closed by the safety-valve. When the distillation is finished, the fire must be dampened or temporarily removed, the passage to the condenser closed by shutting the angle-valve C, the weight removed from the safety-valve, and the valve lifted up and hooked on by the ring-handle to the hook D², affording a free passage from within the still to the open air. The stop-cock in the steam-pipe K is then turned and steam admitted into the still in sufficient quantity to drive out the vapors and gases remaining in the still. When the steam blows out clear and undiscolored from the discharge-pipe G, the steam may be turned off, or be allowed to continue passing through the still for a short time for the purpose of reducing the temperature. The man-holes must now be opened, and the carbonaceous residue immediately removed from the bottom of the still by means of long-handled picks, scrapers, and scoops, the operator standing on the top of the still, it being too hot to enter. If the distillation be not carried to the point of carbonization, which I prefer to do in order to obtain the whole product, the liquid residue may be removed by a suitable withdrawal pipe before turning on the steam. When the residue is removed, the man-holes must be covered, luted, and secured, and the steam again turned on and continued until the atmospheric air and the smoke arising from the ignition of remaining particles of coke is expelled from the still. The safety-valve is then to be let down to its seat and weighted, the passage to the condenser opened by raising the angle-valve C, the charge of oil admitted into the still through the reservoir-pipe J or funnel I, and the steam turned off and fire actively applied to the still.

I consider that steam at a pressure of from forty to sixty pounds to the superficial inch of steam-boiler surface best adapted to the purposes above described; but steam of any sufficient degree of elasticity to expel the matters above described from the still may be used.

By the use of steam as above described I am enabled to make successive distillations in the same still at a high temperature without loss of time other than necessary to remove the residue and charge the still and the time required for the first and second applications of the steam, which is not more than thirty minutes for each application.

The utility of my invention will be apparent to manufacturers using large cast-iron oil-stills, which, in consequence of the thickness of material and the resident heat in the surrounding brick-work, require about twenty-four hours' time to cool naturally before the temperature is sufficiently reduced to admit of introducing the charge of oil without danger of ignition or explosion.

By the use of steam as above described in preparing the still for the reception of the charge oil is safely admitted into the still when the still is at such a temperature that without the presence of the steam the oil would ignite and perhaps an explosion occur.

What I claim as my invention, and desire to secure by Letters Patent of the United States, is—

The use of steam in preparing a hot still for the safe admission of a charge of oil, substantially as described.

LUTHER ATWOOD.
